UNITED STATES PATENT OFFICE.

VICTOR H. VOLAND, OF CLAYTON, MISSOURI, ASSIGNOR TO VOLAND SCENIC STUDIOS, INC., OF ST. LOUIS, MISSOURI, A CORPORATION OF MISSOURI.

HOISTING APPARATUS.

Application filed July 25, 1927. Serial No. 208,123.

This invention relates to hoisting apparatus and is herein illustrated as embodied in a pulley or sheave for use in shifting theatrical drops and pieces of scenery.

5 It is customary to raise and lower stage drops separately by means of several suspension ropes usually attached at points spaced uniformly along a horizontal supporting bar disposed within the top edge 10 of each drop. From the supporting bar the ropes are arranged to run upwardly over sheaves or pulleys resting on a gridiron located directly above the stage, and thence to a wall block and a common counterbalance. 15 The gridiron, which is located high above the stage in which position it is out of the sight of the audience, is generally composed of numerous bars, or iron beams, extending 20 parallel to each other and spaced apart to permit the passage therethrough of the ropes mentioned above.

The gridirons of various stages are often constructed differently, and even the gridiron of a single stage may be made up of 25 beams of different kinds, spaced apart unequally, and having different shapes. As a result of this non-uniform arrangement of the gridiron beams, it has heretofore been customary to secure the sheaves rigidly to 30 the beams and not endeavor to adjust them thereafter. It will be appreciated however that inasmuch as scenic arrangements are constantly being changed and re-arranged on a stage, it would be convenient and highly desirable to provide a sheave that could 35 be adjusted readily, moved from point to point about the gridiron, and secured in a desired position of adjustment, notwithstanding variations in the spacing and shape 40 of the beams to which the sheave is secured.

With the foregoing considerations in mind, the present invention has for an object thereof the provision of an improved sheave which may, with ease and expediency, 45 be secured to, and detached from, supports of different shapes, and to supports spaced apart different distances.

In view of the above designated object, an important feature of the invention re- 50 sides in providing a sheave with a plurality of clamping means which may be adjusted toward and away from each other to vary the distance between the clamping means in accordance with the width of the space be- 55 tween the beams to which the sheave is to

be secured. In the illustrative embodiment of the invention this feature has been obtained by providing the sheave with a frame work having oppositely projecting extensions upon which the clamping members are 60 mounted. These members are mounted in such a manner that they may be adjusted along the extensions, toward and away from the central portion of the frame, where there is located a rotary pulley wheel. It has been 65 found desirable to provide means that will insure against the clamping members slipping or otherwise moving inadvertently along the extension of the frame, thereby disengaging the sheave from the support and 70 rendering it liable to fall from the stage gridiron with a probability of injuring some one on the stage beneath, and consequently, as illustrated, the upper surface of the extensions are provided with notches into 75 which grooves formed upon the clamping means are adapted to be seated. By virtue of such an arrangement the danger of the sheave becoming loose and falling from its support is eliminated. 80

Another feature of the invention consists in the provision of a sheave in which the depending portion of a rope passing through the sheave will extend through the base of the frame of the sheave at substantially the 85 central portion thereof. In the illustrated embodiment of the invention this feature is obtained by making the oppositely extending projections of the frame of unequal lengths; the projection of the frame on the 90 side of the sheave from which the rope depends being longer than the opposite projection. Such a provision insures that the depending rope will always be positioned substantially centrally of the space between 95 the beams upon which the sheave is supported, thereby avoiding all danger of the depending portion of the rope becoming fouled on the beams.

Still a further feature of the invention 100 consists in providing a sheave of this character with a guard which may be removed with ease and expediency to permit ready removal of the pulley wheel from the frame, or the quick insertion of a new pulley wheel 105 into the frame.

While the invention has been illustrated and described herein with particular reference to its use in stage work, it is to be recognized that the invention may be employed 110

beneficially in any kind of work requiring the use of hoisting apparatus generally.

The above and other features and objects of the invention will become apparent from a reading of the following specification in the light of the accompanying drawings, in which:

Fig. I shows, in perspective, a view of my improved sheave.

Fig. II is a view in front elevation of the device disclosed in Fig. I.

Fig. III is a vertical view, in section, showing the manner in which the pulley wheel is mounted within the sheave.

Fig. IV is a detail view showing the manner in which the sheave may be secured with equal facility to a support entirely different from the support disclosed in Fig. I.

As shown in the drawings the reference numerals 10 indicate vertically extending beams provided with flanges 12, and, as illustrated, these beams are of a type commonly employed in a gridiron of stages to serve as supports for various hoisting apparatus that is used in shifting scenes and scenery.

The illustrated embodiment of my invention is shown in Figs. I, II and III as being supported upon the beams 10 by means of clamping plates 14, secured to a frame 16 which is arranged to support a rotary pulley wheel 18. The frame 16 is provided with oppositely extending projections 20, 22 having a series of notches 24 formed in their upper surfaces for cooperation with blocks 26 (Fig. I) having grooves 28 formed within their lower surfaces. Clamping bolts 30 extend between the blocks 26 and the clamping plates 14, and butterfly nuts 32 are provided for the purpose of imparting clamping pressure to the plates 14.

As shown in Figs. I, and II the plates 14, which are L-shaped in cross-section, may be adjusted along the smooth, under-surface of the frame 16 until they are in over-lapping engagement with the flanges 12 of the beams 10. At this time the blocks 26 may be moved into engagement with the notches 24 and the butterfly nuts 32 may be tightened, thereby securing the entire sheave in rigid engagement with the beams upon which it rests. As hereinbefore pointed out, the beams used in the gridirons of different stages, or even the beams used within a single gridiron are oftentimes of different shapes and arranged in a different manner such, for example, as indicated in Fig. IV of the drawings. As here shown, the beams are arranged with flanges 34 projecting downwardly and with

flat upper surfaces 36 upon which the projections or extensions of the frame are adapted to be seated. In securing the sheave to a support of this character, the clamping plates 14 are adjusted away from the smooth under-surface of the frame 16 until they are

so located as to span the flanges 34 of the beams, in which position the butterfly nuts 32 may be tightened to secure rigidly the sheave in its seated position. While the sheave has been illustrated herein as secured to beams of only two different types, it will be appreciated that the clamp plates 14 are of such a shape and construction as to permit the sheave to be secured to supports of innumerable shapes.

As shown in Fig. II the extensions 20, 22 of the frame 16 are of unequal length, the extension 22 on the side of the pulley wheel 18 adjacent to the downwardly extending portion of the rope 38 being longer than the opposite extension 20. The purpose of constructing the extensions in this manner is to avoid all danger of the rope 38 becoming fouled upon the beams 10 of the stage grid. Since the downwardly extending portion of the rope is off-set from the center of the wheel 18 by a distance equal to the radius of the wheel, the extension 22 is, as above stated, made longer than the extension 20 thereby permitting the pulley wheel 18 to be located to the left (as shown in Fig. II) of the center of the space between the beams 10, 10, and the rope 38 to descend substantially near the center of such space, free and clear of the supporting beams.

In the use of devices of this character, it is often desirable to substitute rotary pulley wheels of different diameters or to insert a new wheel when an old one becomes worn or broken. The illustrated sheave is constructed in such a manner that the wheel 18 may be quickly and easily removed from the frame 16 to permit insertion in the frame of a new wheel. Accordingly, and as illustrated, the frame 16 is provided with upwardly extending ears 40 (Fig. III) having openings therein to receive a pin or gudgeon 42 upon which the pulley wheel is adapted to rotate. A guard 44 is mounted upon the projecting ears 40 of the frame 16, and is provided with depressions 46 for receiving the ears 40. In operation, the pin 42, which as illustrated, is secured in place by means of a cotter-pin, may be extracted and the guard and pulley be then removed without removing from the sheave the rope 38 which passes therethrough. A new pulley may be then inserted between the ears 40 of the frame 16, and the guard 44 re-positioned down over the ears, the depressions 46 formed within the guard engaging the ears 40, thereby acting as a self-centering device in alining the holes in the guard with the holes in the ears.

It will be noted from an inspection of Fig. III that the bottom of the frame 16 is cut away to permit the passage therethrough, and adjustment therewith, of the rope 38, and the clamping bolts 30, respectively. The frame 16 is, however, provided with out-

wardly turned flanges 50 which serve to provide a flat under-surface on the frame 16.

Having thus described my invention what I claim as new, and desire to secure by Letters Patent of the United States is:—

1. A sheave of the character described comprising a frame having a rotary pulley wheel mounted therein, and a plurality of extensions projecting from opposite sides 10 of the frame, said extensions being formed on one side with smooth faces and on the other side with a series of notches for securing in a desired position of adjustment clamping plates arranged to cooperate with 15 the smooth faces of the extensions.

2. A sheave of the character described comprising, in combination, a pulley wheel, a frame for supporting the pulley wheel, extensions projecting from opposite sides of

the frame, a series of notches formed within said extensions, blocks having grooves formed on one of their faces for co-operation with the notches formed within the extensions, and clamping plates carried by said blocks and arranged for adjustment therewith lengthwise of said extensions. 20 25

3. A sheave of the character described comprising a rotary pulley wheel, a frame for supporting the wheel, said frame being provided with a plurality of upwardly extending ears having bearings formed therein, and a removable guard for the pulley wheel, said guard being formed with depressions for receiving the upwardly extending ears of the frame. 30 35

In testimony that I claim the foregoing I hereunto affix my signature.

VICTOR H. VOLAND.
